UNITED STATES PATENT OFFICE.

WILLIAM A. HARNETT, OF PHILADELPHIA, PENNSYLVANIA, ASSIGNOR TO FRANCES A. HARNETT, OF PHILADELPHIA, PENNSYLVANIA.

COMBINED CESSPOOL AND RAIN-SPOUT CONNECTION.

No. 890,276.

Specification of Letters Patent.

Patented June 9, 1908.

Application filed June 18, 1907. Serial No. 379,600.

To all whom it may concern:

Be it known that I, WILLIAM A. HARNETT, a citizen of the United States, residing at Philadelphia, in the county of Philadelphia and State of Pennsylvania, have invented a certain new and useful Improvement in a Combined Cesspool and Rain-Spout Connection, of which the following is a specification.

10 My invention relates to a new and useful improvement in combined cess-pool and rain spout connection, and has for its object to provide an exceedingly simple and effective device of this construction which will serve 15 as the ordinary cess-pool and at the same time permit the drain pipe from the building for carrying off the rain to be connected therewith.

With these ends in view, this invention consists in the details of construction and combination of elements hereinafter set forth and then specifically designated by the claims.

In order that those skilled in the art to which this invention appertains may understand how to make and use the same, I will describe its construction in detail, referring by letter to the accompanying drawing forming a part of this specification, in which—

Figure 1 is a plan view of my improved 30 combination cess-pool and drain pipe connection. Fig. 2, a section at the line X—X of Fig. 1. Fig. 3, a similar section of a slightly modified form of my invention.

In carrying out my invention as here embodied, A represents the casing of the cess-pool with which the pipe B is formed, said pipe being intended to lead to the sewer and also to serve as the connection for the drain pipe or leader from the rain pipes of the building or other such pipes, the upper portion of the pipe B being enlarged or bell-shaped to permit the insertion of a drain pipe or the like. The bottom of the casing is inclined toward the pipe B so water will readily flow 40 therefrom into said pipe through an opening formed in pipe B above its junction with the inclined bottom of the casing A.

C represents the cover of the cess-pool and is adapted to fit upon the casing. The removable cover C is of rectangular form and has a central saucer shaped portion, perforated at D which saucer shaped portion seats upon the edge of the casing A. Said cover is provided along its edges with a continuous 50 upstanding flange having a bend to accom-

modate the bell shaped mouth of the pipe B, the flange at this point contacting with said pipe and serving to accurately center the cover in position as shown more particularly in Figs. 1 and 2. The perforations D permit 60 of the passage of liquid and yet are too small to allow of the passage of refuse, which is held back in the saucer shaped portion.

My improvement greatly facilitates the making of the connection between the rain 65 drainage pipes of a building and the cess-pool and avoids the necessity of taking up two portions of the yard to locate the cess-pool and pipe connection.

While I have shown the pipe for the drain 70 pipe connection and the cess-pool cast in one piece it is obvious that these may be made separate and secured together in any suitable manner.

In the modification shown in Fig. 3 I have 75 illustrated a slightly varied form of my improvement in which the cess-pool A' has formed therewith or connected thereto the sewer pipe A' while the drain pipe connection B' leads into the cess-pool so that water 80 flowing therein will first flow to the cess-pool and then to the sewer pipe connection A'.

Having thus fully described my invention, what I claim as new and useful, is—

1. As a new article of manufacture a cess 85 pool comprising a casing, open at its upper end and having an inclined bottom, and a pipe at one side of the casing having an opening above the lower end of said inclined bottom and communicating with the casing, 90 said pipe being arranged to have a portion thereof at one side of the casing forming a continuation of the wall of the casing.

2. As a new article of manufacture a cess 95 pool comprising a casing, open at its upper end and having an inclined bottom and a vertical pipe disposed wholly at one side of said casing having an opening above the lower end of said inclined bottom and communicating with the casing, said pipe forming a part of the vertical wall of said casing.

3. As a new article of manufacture a cess 105 pool comprising a casing, open at its upper end and having an inclined bottom, a vertical pipe disposed at one side of the casing and forming one wall thereof, said pipe having an opening in communication with the casing and above the lower end of the inclined bottom and a displaceable cover comprising a saucer shaped portion and a portion pro- 110

jecting therebeyond, said saucer shaped portion seating on the upper edge of said casing, said projecting portion having its edge adjacent said pipe shaped to conform to and 5 lying in contact with said pipe.

4. As a new article of manufacture, a cess pool comprising a casing, open at its upper end and having an inclined bottom, a vertical pipe disposed at one side of the casing 10 and forming one wall thereof, said pipe having an opening in communication with the casing and above the lower end of the inclined bottom and a displaceable cover comprising a saucer shaped portion, and a por-

tion projecting therebeyond, said saucer shaped portion seating on the upper edge of said casing, said projecting portion having at its edge an upstanding flange which is formed with a bend adjacent to and lying in contact with said pipe. 15

In testimony whereof, I have hereunto affixed my signature in the presence of two 20 subscribing witnesses.

WILLIAM A. HARNETT.
